ODORIZER FOR NATURAL GAS

William A. Green, Jonesboro, Ark., and Edward Rolle, New York, N. Y., assignors to Standard Oil Company of California, San Francisco, Calif., a corporation of Delaware

Application May 24, 1938, Serial No. 209,690

3 Claims. (Cl. 261—39)

This invention relates to devices for introducing a volatile material having a distinctive odor into a confined flowing stream of gas, and particularly refers to an apparatus for accurately controlling the rate of evaporation of a volatile odorant material and introducing the gas thus formed into a natural gas line at a rate proportional to the rate of gas flow in said line.

Heretofore it has been proposed to introduce odorant liquid into a gas line by means of differential pressure set up therein and used to control the flow of the liquid through a small orifice, with constant level float chambers, and other moving and delicate parts that are susceptible to leakage, corrosion and failure to operate reliably over long periods without attendance. Those evaporative types that have been used are subject to atmospheric temperature variations that change the rate of evaporation of the liquid and hence the odorizing rate. Also, they do not continuously present an odorant of the same characteristics, particularly where the odorant material is not of a constant or nearly constant boiling mixture.

It is an object of this invention to provide an improved evaporative odorizer for natural gas, in which variations in odorant liquid level will have no effect on the odorizing rate.

Another object is to provide an odorizer that will provide a constant odorizing rate independently of variations in atmospheric temperature.

Another object is to provide an odorizer that will have a minimum of moving parts, that will not be susceptible to clogging or stoppage of small passages, valves, or orifices, that may be used with very low pressure differentials such as those produced by Pitot tubes in the gas line, and that will not cause changes in the composition of the odorant materials of relatively wide boiling range being presented to be evaporated into the gas stream passing through the device.

These and other objects and advantages will be more fully apparent from the following description and from the drawing which forms a part of this specification and illustrates a preferred embodiment of the invention as applied to a natural gas odorizer.

In the drawing, Figure 1 is a diagrammatic vertical sectional view of an odorizer installation.

Figure 2 is an enlarged detail view on line II—II of odorizer of Figure 1, showing a vertical section of preferred float construction.

Figure 3 is a horizontal sectional view on line III—III of the float shown in Figure 2.

Referring to the drawing, the reference numeral 10 designates a gas line in which flows the gas to be odorized, in the direction indicated by the arrow. Some means of creating a pressure differential is provided, in this case a Pitot tube 11 forming the high pressure connection and a simple nipple 12 forming the low pressure connection. An orifice or partly closed gate valve 10 in line 10 could equally well be used, but a Pitot tube as illustrated has certain advantages of installation without interfering with the operation of gas line 10 that may make it desirable under certain circumstances.

The main part of the odorizer comprises an upright tubular housing 13, preferably separable by means of a pair of bolted flanges 14 to permit access to the interior. An odorant storage tank 15 is arranged near the housing 13 and is preferably mounted horizontally to give minimum variations in liquid level, as will be apparent below. A pipe 16 with a shut-off valve 17 and a flow restricting means, in this example a check valve 18 connects the lower portions of housing 13 and tank 15. The check valve or other restriction insures that the odorant liquid 19 will flow only from the tank to the housing so that the odorant in the lower part of housing 13 will be uniform in composition. The upper portions of tank 15 and housing 13 are connected by an equalizing line 20, preferably fitted with a pressure release valve 21. A filling nozzle 22 is mounted on tank 15.

In order to divert a part of the gas passing through line 10 into housing 13, a conduit 23 leads from Pitot tube 11 upwardly into housing 13 preferably coaxially therewith to a point above the highest possible odorant liquid level therein. A gas outlet conduit 24 at the top of housing 13, preferably provided with a packed screen or other type of mist extractor 25 leads downwardly to nipple 12 in gas line 10. It is desirable, although not necessary, to provide shut-off valves 26 and 27 in lines 23 and 24 respectively, and a by-pass 28, also provided with a valve 29, for adjustment and inspection of the device. A gage glass 30 on the side of housing 13 indicates the level of odorant liquid 19 therein, and may be used to calibrate the device, as will be explained below.

A float generally designated 31 is mounted in housing 13 and acts to insure uniform contact between the gas being diverted through the device and the relatively small quantity of odorant

liquid 19 in housing 13. Referring to Figure 2 it will be noted that float 31 comprises an inverted cup 32, from the center of which a long closed tube 33 extends upwardly to a distance 5 greater than the length of pipe 23, and which serves to direct downwardly the gas which enters the housing through pipe 23. Below the lower edge of cup 32 are concentric reticulated cylinders 34 and 35, which may be of perforated 10 sheet metal or metal wire screen construction, and with the annular space between them packed with a fibrous material 36 such as steel wool, to provide an extended surface or capillary member and insure that all gas passing around 15 the lower edge of cup 32 will be saturated with odorant liquid.

At the lower end of cylinders 34 and 35 is a supplemental float which may be of balsa or other light buoyant material 37 covered with light 20 sheet metal 38. A guide tube 39 extends upwardly from the opening 40 in the center of the float structure and serves to center and align the whole with pipe 23. The proportions of weight 25 of float 31 and buoyancy of member 37 are such that the lower edge of cup 32 is preferably substantially at the level of the odorant liquid. If greater submergence is required, annular weights 41 guided by pins 42 may be placed on the top of cup 32 as indicated.

One of the principal disadvantages of the evaporative types of odorizers heretofore used was the variation in odorization rate with atmospheric 30 temperature changes, high temperatures increasing the evaporation rate and low temperatures retarding it. This invention includes the provision for keeping the relatively small quantity of liquid odorant in the housing 13 at a constant temperature, preferably at a fairly high value, so that the amount of gas by-passed or diverted through the 35 device will be small, and also so that extraordinarily high atmospheric temperatures such as are sometimes encountered, will not affect its operation. To this end, the housing 13 and, if desired, tank 15 may be insulated as shown at 43, using 40 any desirable form of thermal insulating material, and means are provided to heat the odorant 19 in housing 13, as by a suitable electric heating element 44, controlled by a thermostat 45 and energized from a source of electric current 46. Obviously other means for heating, such as a gas 45 fired device, a steam or water heater could be substituted for these heating means, if circumstances warrant.

In operation gas is diverted from line 10 50 through Pitot tube 41 at a rate directly proportioned to the gas flow in line 10, and passes through line 23 into the upper end of tube 33 of float 31, whence it is deflected downwardly into inverted cup 32 from which it passes through odorant saturated packing 36 and around the lower edge of cup 32 and thus becomes saturated with the odorant liquid 19. This now saturated gas passes out of housing 13 through mist extractor 25 and conduit 24 and back into line 10, where it diffuses into the remaining gas in line 10 and serves to give it the distinctive odor required for safe 55 operation of natural gas systems, which odor is inherently lacking in natural gas as it comes from

the well. As an example, using "Calodorant" gas odorizing liquid described and claimed in U. S. Patent No. 2,094,270 issued September 28, 1937, and with an odorant temperature of 140° F. in the housing 13, a diversion of 0.1% of the gas 5 passing through line 10 absorbed sufficient odorant to give a concentration of 2 gallons per million feet of gas. Preferred ranges of odorization range from 2 to 3 gallons of that material per million cubic feet of natural gas. 10

As the relatively small quantity of odorant 19 in the lower part of housing 13 becomes depleted through evaporation, added odorant liquid automatically flows in through line 16 and valves 17 and 18, the latter serving to maintain a constant 15 concentration of odorant in housing 13 and preventing accumulation of heavy ends or high boiling constituents of that liquid.

Float 31 will follow the odorant level as it is lowered by evaporation and will hold the sub- 20 mergence of cup 32 and the capillary element carried thereby constant. Gage glass 30 will indicate when tank 15 needs refilling. To calibrate the device valve 17 may be closed, whereupon no more odorant will flow into housing 13 from tank 25 15 and gage glass 30 will indicate the rate of evaporation of the odorant 19. Suitable metering apparatus in gas line 10 (not shown) may be used to determine rate of flow in that line.

Although a specific arrangement and construction of an apparatus embodying this invention has been described and illustrated above, it will be understood that many changes could be made therein without departing from the invention, and all such modifications as come within the scope 30 of the appended claims are embraced thereby.

We claim:

1. An evaporative type odorizer, comprising an upright housing, an odorant reservoir, a conduit connecting the lower portions of said housing and said reservoir, means in said conduit for permitting gravity flow from said reservoir to said housing and preventing reverse flow, a float in said housing, a capillary means supported by said float to contact and be uniformly wetted by said odorant liquid independently of the level thereof, means for passing gas into said housing through said wetted capillary material above the level of said odorant liquid, a gas outlet from said housing and means for maintaining the temperature of the odorant liquid in said housing at a constant value to provide a constant odorizing rate.

2. An evaporative type odorizer according to claim 1 with the addition of a pressure equalizing 55 conduit connecting said housing and said reservoir above the liquid level.

3. An evaporative type odorizer according to claim 1 in which said float comprises an inverted cup beneath which gas is admitted, guide means 60 for said cup, and capillary means disposed below the lower edge of said cup and extending above the level of the liquid in said housing, through which means gas emerges into said housing and is at least partially saturated with said odorant 65 liquid.
